CABLE CONNECTOR

John R. Frank, St. Charles, and Walter Allen
 Plagenberg, Sr., Berkeley City, Mo., and Everett
 B. McCarty, Alton, Ill.

Application May 7, 1947, Serial No. 746,586

10 Claims. (Cl. 285—6.5)

1 This invention relates to novel and useful improvements in cable connectors utilized principally in electrical junction points.

An object of this invention is to provide a cable connecting means adaptable to various sizes of cables as well as various types of cables.

Another object of this invention is to provide an improved pivoted cable engaging means within said cable connector.

Another object of this invention is to provide adjustable locking means, engageable with said cable engaging means.

A still further object of this invention is to provide means for compensating or expansion and contraction of said cable engaging and connecting means.

A further object of this invention is to provide detachable shim means to partially compensate for various side cables utilized in connection with the present invention.

Another object of this invention is to provide an extremely simple and dependable device of this character which lends itself well to commercial manufacture.

Ancillary objects and features of novelty shall become apparent to those skilled in the art, in following the description of the preferred embodiment of the present invention, illustrated in the accompanying drawings wherein:

Figure 1 is an elevational side view of the preferred embodiment of the present invention;

Figure 2 is a sectional view of the invention disclosed in Figure 1, portions shown in elevation for clarity;

Figure 3 is an elevational front view of the invention disclosed in Figure 1, the cable removed;

Figure 4 is a transverse sectional view of the invention disclosed in Figure 1;

Figure 5 is a fragmentary elevational view of the invention disclosed in Figure 1 taken on the other side thereof;

Figure 6 is a perspective view of the pivoted cable engaging means, and

Figure 7 is a perspective view of the shim used in conjunction with the present invention.

Referring now in detail to the illustrative preferred embodiment of the present invention, like reference characters are used throughout to indicate similar elements.

This invention has been developed to provide a device for receiving electrical conducting apparatus therein and retaining the same in a predetermined position. The prime use of the present invention is with cable (of various, conventional

natures) however, it is within the purview of this invention to utilize the same with other types of conduits in various environments. The preferred material of construction is metallic however, other material might be utilized, if so desired.

A housing 10, preferably annular in configuration, is provided with a flared end portion 12 thereon. A collar 14 is received on said flared portion 12 and may be pressed or otherwise secured thereon. At selected portions along the longitudinal axis of said housing 10, there is formed a pair of annular shoulders 16 and 18 respectively. These shoulders are utilized in retaining the invention within a conventional outlet box 20. The space between the said shoulders 16 and 18 is occupied by the usual face of the outlet box 20 after forcing the invention therein. A cable 22 is received in the sleeve-like housing

10. The travel of the housing 10 on the cable 22 is limited by means of the lug 24 engaging the terminal portion thereof.

In order to retain the cable 22 in a fixed, immovable position relative to the housing 10, a baffle means is provided in the housing. This baffle means may be viewed in Figure 6 wherein there is disclosed an arcuate plate 28 having a reduced shank portion 30 extending therefrom and pads 32 on said reduced portions. The reduced portions 30 and pads 32 extend through a suitable slot 34 extending longitudinally of said housing 10. The said slot 34 has an enlarged portion 36, specifically provided for the purpose of receiving the above mentioned portions 30 and 32 respectively. After the baffle plate 28 is received in the desired position, the pads 32 are bent slightly to provide a locking means. By this construction, pivotal movement of the plate 28 is permitted yet the said plate 28 is not permitted to fall out of the housing 10. In other words, movement of the plate 28 is restricted to pivotal motion.

A suitable threaded aperture is provided in the housing 10 for the purpose of receiving an adjusting means therein. This adjusting means is preferably a set screw 39 which abuts a suitable slot, detent or cam track 40 in the said plate 28. Inspection of Figure 2 discloses that the said screw 39 holds the plate 28 into fixed relation with the said cable 22.

Diametrically opposite the said slots 34 in a housing 10 there is provided a second slot 42 which extends substantially the full length of the housing 10, terminating adjacent but not at the terminal portions thereof. The said slot 42 is

utilized as an expansion and contraction means, for compensation of various factors as in pressing the housing within the box 20.

When the invention is utilized with smaller types of cables, a shim 45 preferably arcuate in configuration is supplied at the base of the housing 10. Legs 46 depend from the shim 45 for the purpose of engaging the inner bore of the housing 10. This last mentioned shim element is optional in nature, being utilized only when cables of relatively small cross-sectional areas are employed.

In retaining the housing 10 within the electrical box (or other junction apparatus), after placing the shoulders 16 and 18 on opposite sides of the wall 20, the screw means 39 is tightened not only securing the cable 22 within the housing 10, but also separating the housing to effectively lock the same within the electrical box.

While there has been described and illustrated a device capable of performing all of the specifically mentioned objects as well as numerous ancillary objects, it is apparent to those skilled in the art that various changes including omissions and additions may be made herein without departing from the spirit of the invention. Accordingly, limitation is sought only in accordance with the scope of the following claims.

Having thus described the present invention what is claimed as novel and improved is as follows:

1. A cable connector comprising a housing, means for securing said housing to a receptacle, a slot in said housing, cable engaging means pivoted in said slot, means for adjustably urging said cable engaging means, a shim in said housing.

2. A cable connector comprising a housing, means for securing said housing to a receptacle, a slot in said housing, cable engaging means pivoted in said slot, means for adjustably urging said cable engaging means, a shim in said housing and an expansion slot in said housing.

3. A cable connector comprising a housing, means for securing said housing to a receptacle, a slot in said housing, cable engaging means pivoted in said slot, means for adjustably urging said cable engaging means, a shim in said housing and an expansion slot in said housing, said cable engaging means comprising an arcuate baffle having a reduced portion extending through said slot and lock means on said reduced portion.

4. A cable connector comprising a housing, means for securing said housing to a receptacle, a slot in said housing, cable engaging means pivoted in said slot, means for adjustably urging said cable engaging means, a shim in said housing and an expansion slot in said housing, said cable engaging means comprising an arcuate baffle having a reduced portion extending through said slot and lock means on said reduced portion, an arcuate detent in said baffle, said adjustable urging means including a set screw extending through said housing and engaging said detent.

5. Means for retaining cables in a fixed position comprising a sleeve having a longitudinal slot and an enlargement of said slot, cable engaging means pivoted in said enlargement, locking means on said cable engaging means, means for retaining

said cable engaging means in a predetermined fixed position operatively engaging and forming a portion of said locking means, expansion means in said sleeve.

6. Means for retaining cables in a fixed position comprising a sleeve having a longitudinal slot and an enlargement of said slot, cable engaging means pivoted in said enlargement, locking means on said cable engaging means, means for retaining said cable engaging means in a predetermined fixed position engaging and forming a portion of said locking means, expansion means in said sleeve, and further means for reducing the bore of said sleeve detachably received in said sleeve.

7. Means for retaining cables in a fixed position comprising a sleeve having a slot and an enlargement of said slot, cable engaging means pivoted in said enlargement, locking means on said cable engaging means, means for retaining said cable engaging means in a predetermined fixed position engaging and forming a portion of said locking means, expansion means in said sleeve, said locking means comprising flanges on said cable engaging means abutting said sleeve.

8. Means for retaining cables in a fixed position comprising a sleeve having a slot and an enlargement of said slot, cable engaging means pivoted in said enlargement, locking means on said cable engaging means, means for retaining said cable engaging means in a predetermined fixed position, expansion means in said sleeve, said locking means comprising flanges on said cable engaging means abutting said sleeve, said retaining means comprising a set screw in said housing seating on said cable engaging means.

9. Means for retaining cables in a fixed position comprising a sleeve, a slot in said sleeve, an enlargement of said slot, cable engaging means pivoted at one end thereof in said enlargement, locking means on said cable engaging means, means for retaining said cable engaging means in a predetermined fixed position, expansion means in said sleeve, said expansion means comprising a slot extending longitudinally of said sleeve and terminating adjacent the ends thereof.

10. A cable connector comprising a housing having slot means therein, common means in said housing for retaining cable in said housing and for securing said housing to a junction box, said means including spaced shoulders on said housing adapted to receive the wall of a junction box therebetween, cable engaging means pivoted at one end in said slot and including a cam track, adjustable means in said housing engaging said cam track and expanding said housing.
